A diagram showing a long, thin tube coiled vertically. The tube is labeled with various numbers: 193 at the top, 194 on the left side, 170 on the right side, 189 on the left side, 190 on the right side, 192 at the top right, 192 at the bottom right, and 172 on the right side of the coil. The tube has a flared end at the bottom.

A diagram of a long, thin, segmented tube. The tube has a central cavity and is shown in three segments. There are three ports or openings on the tube: one on the left labeled '171' and two on the right labeled '170'. The tube is oriented horizontally.

Application February 5, 1940, Serial No. 317,321

9 Claims. (CL 206—56)

This application is a continuation-in-part of application Serial No. 266,608, filed April 7, 1939.

This invention relates to package structures and it has among its objects a package structure in which the empty ends of a plurality of bag-like containers enclosing the substance, such as powders, granules, tablets and the like, which is to be dispensed, are freely suspended, by their empty ends only, in one or more rows within a recess of a protective sheet structure which is shaped to form a cover which encloses and protects all the individual containers, while enabling ready and convenient dispensing of the contents of each container unit by merely tearing off its empty end along the edge of the sheet portions forming the recess.

The foregoing and other objects of the invention will be best understood from the following description of exemplifications thereof, reference being had to the accompanying drawings wherein

Fig. 1 is a perspective view illustrating one form of a package structure of the invention;

Fig. 2 is an end or sectional view along line 2—2 of Fig. 3;

Fig. 3 is an elevational view of the package structure of Fig. 1 with parts of the front cover broken away;

Fig. 4 is a perspective view of one of the dispensing containers of Fig. 1 and its junction to the mounting strip;

Fig. 5 is a view similar to Fig. 2 illustrating a different form of such package structure;

Figs. 6 and 7 are views similar to Figs. 2 and 3 illustrating another form of such package structure;

Fig. 8 is a cross-sectional view along line 8—8 of Fig. 7;

Figs. 9 and 10 are views similar to Figs. 2 and 3 illustrating a still other form of the invention;

Fig. 11 is a view similar to Fig. 2 illustrating a further form of the invention;

Fig. 12 is a cross-sectional view along line 12—12 of Fig. 11;

Figs. 13 and 14 are views similar to Fig. 2 illustrating other forms of the invention;

Fig. 15 is an elevational view of another form of the invention;

Figs. 16 and 17 illustrate two ways of making container assemblies for a package structure of the invention;

Figs. 18, 19 and 20 are perspective views of different types of dispensing containers and their

sheet strip mounting suitable for making package structures of the invention;

Fig. 21 is a view similar to Fig. 2 of a further form of the invention;

5 Figs. 22, 23 and 24 illustrate three stages in the formation of container assembly units for a form of package structure of the invention such as shown in Fig. 21;

Fig. 25 is a cross-sectional view across a container unit of Fig. 24;

Figs. 26 and 27 are views similar to Figs. 22 and 23 illustrating another way of making container assembly units for a package structure of the invention;

10 Figs. 28 and 29 are cross-sectional views illustrating different ways of forming container units or package structures of the type shown in Figs. 26 and 27; and

Fig. 30 is a view similar to Fig. 2 illustrating another form of the invention.

15 A great variety of package structures have been used for many years past for dispensing powder, granular, pill, tablet and similar products that are sold to the public for household, medical and other uses.

20 Many products that are sold in powder, granular, pill, tablet and similar forms and are designed for use in small quantities only, are being packed in tins, boxes or like containers. Since 25 the contents of such containers are easily spilled and the containers are often broken, a large part of the product is wasted. Although some of these are protected by a tough lining, they are subject to contamination and deterioration, by 30 dampness, for instance, incident to repeated opening of such containers.

35 In connection with many of such products, it has been long realized that it would be of great advantage if they could be packed and shipped 40 in a package structure that would make possible dispensing of the product in exact measured fractional amounts required for each use, and enable convenient dispensation of each fractional amount while keeping the contents of the other units sealed and protected until required 45 for use.

40 The invention solves the problem of packaging and dispensing such products, in any desired measured quantities, by the provision of 50 a novel multi-container sanitary-dispensing package structure, which is suggestive of a matchbook, and comprises a protective sheet enclosure having a backing sheet and a cover sheet folded thereover and holding protected in the 55 interior, a row of baglike, tearable product con-

ainers or packets, which are joined to the protective sheet enclosure solely by their empty ends, in such manner that the entire length of each container is freely suspended for enabling the individual removal of each individual container by merely tearing it off from its junction.

The protective sheet enclosure has a backing sheet and a cover sheet folded thereover to protect the interior space between said sheets, and a relatively narrow overlying retaining sheet strip extending over a portion of said backing sheet. This cover or wrap may be made of a material, such as paper-board or the like, and has sufficient strength to both protect and carry the filled and usually more fragile dispensing packets. The relatively narrow overlying retaining sheet strip may be of a material similar to the cover, as when formed by the folding of an integral portion of the backing sheet, or of other suitable and convenient materials when not so formed.

The retaining sheet strip extends over a portion of said backing sheet to form along the interior surface of said backing sheet an elongated recess bounded by an edge of said strip.

An additional sheet strip and a row of a plurality of tearable baglike containers extending from said additional strip are fastened behind the edge of said overlying retaining sheet strip within the recess formed on said backing sheet. The additional sheet strip may be inserted in the recess adjacent to the empty container ends to give additional rigidity and padding to the structure. It may be formed by an extension of the retaining sheet strip. It may be a separate element to which the containers are attached, or it may be integral with the containers.

The individual containers hold sealed in expanded portions of their interior fractional amounts of a dispensable substance. The fastened end portion of each container constitutes the sole junction of the container to the backing sheet and to the other containers fastened to said backing sheet. Thus, substantially the entire filled length of each container is freely suspended in front of said backing sheet so that each may be removed individually by merely tearing it off across the edge of one of said sheet strips. Tearing off the empty end of the container, while the thumb of the other hand acts as a backing support for the cutting edge, makes available to the user that single dose in an opened bag.

Tearable material, such as paper, wax paper, glassine, metallic foils, and the like are suitable for making dispensing containers. Tough sheet materials, such as cellulosic or rubber hydrochloride sheets may also be used, with a metallic or other strong cutting edge provided along the edge of the retaining recess in which the empty ends of such containers are fastened, to facilitate the tearing off of the empty binding ends of the containers.

Alternatively, the empty end portions of the containers may be made of cellulosic material, or materials having similar properties, and may be weakened to permit easier tearing and the elimination of stronger cutting edges than those provided by a single overlying sheet strip of cardboard, or the like. This weakening operation, as by heat or other means, may form a step in the process of the formation of the bag-like dispensing containers, or of the sealing operations after they have been filled, or take place at the time they are bound within the recess.

Elongated envelope-type or bag-type containers, suitable for dispensing containers, have long been known and are in wide daily use. Mass production methods and machines are generally available for inexpensively making, imprinting, filling and sealing such containers, and for automatically handling them through subsequent steps. This is also true as to the imprinting, cutting, folding and other operations in the formation of the protective cover wraps, and the binding operations incidental to completing the finished package structure.

Thus, standard packaging machines and equipment, with but minor changes and adjustments, may be economically employed to produce sanitary dispensing packages of the invention. And special machines may be easily designed to produce container assemblies from a continuous sheet roll, the baglike individual dispensing units integrally extending from a common sheet strip, as a fringe, and they may also be filled and sealed automatically, and cut off into convenient lengths or sections, either before or after being fed by their integral sheet strip into the binding recess on the cover.

Alternatively, to facilitate handling, the individually made, filled and sealed dispensing containers may be fed to and assembled laterally upon a sheet strip of suitable and convenient material, such as paper, paper-board, or the like, their empty ends secured as by spotting, cementing, fusing or crimping with or without heat, so that they are attached to and extend from it as a fringe. Depending upon the substance being packaged, the filled containers may first be subjected to an agitating or shaking action to settle the contents and leave one end empty for binding, unless the sealing section is deep enough to keep sufficient area flat and empty for such operations.

Figs. 1 to 3 illustrate a package structure exemplifying one form of the invention. It comprises an enclosure sheet, of hard calendered cardboard, for instance, folded into a book-like cover structure composed of a backing sheet 40 having on one side a recess 41 formed by an integral overlapping sheet portion 42, and on the other side a cover flap 43, the free edge of which is inserted and held behind the edge 44 of the recess strip 42 when the package structure is closed, in the way shown in Fig. 3. A plurality of elongated baglike containers 45, each previously filled, through their open upper ends, with the substance which is to be dispensed, are shown assembled adjacent to each other in two rows on opposite sides of a relatively stiff binding or mounting strip 46, with their upper empty ends clamped and sealed within the recess 41 of the cover sheet.

In the form shown in Figs. 1 to 3, the container bags are of the satchel or square-end gusset type. As illustrated in Fig. 4, they may be assembled by fastening their upper empty ends on the opposite sides of a mounting strip 46 which may have an edge 47 projecting slightly beyond the edge 44 of the recess strip 42 of the cover structure. The bags may be of wax paper, for instance, and the open upper empty ends of two rows of such bags may be sealed and fastened to the opposite sides of the mounting strip 46 by heat and pressure in a continuous production process. Both side walls of each bag may be either of equal height, or the side facing the mounting strip 46 may be somewhat shorter than the outer side so that only the junction of the overlapping side

wall portions of the bag to the mounting strip serves as a seal for the contents of the bag.

The clamping junction between the end portions of the empty ends of the rows of container-bags 45 and the wall portions of the recess 41, within which they are clamped, may be effected either by a cementitious material, or by means of anchors, such as staples 49, extending through, and clamped over, the opposite sides of the cover sheet bordering the recess or stitching across the entire length may be used. Obviously, a cementitious material as well as staples may be used for securing the clamping junction between the end portions of the empty ends of the bags with the side walls of the recess 41.

The edge 44 of the integral recess strip 42 overlying the front row of bags 45 and the edge 41 of the mounting strip overlying the next row of bags 45 are made of sufficient stiffness so as to serve as cutting edges across which each bag may be torn off by pulling it outwardly with one hand while the thumb of the other hand backs up and supports the recess strip 42.

In the package structure of the type described above, each bag hangs freely by its empty end which forms its sole junction to the other bags and to the cover structure. A person desiring to use the contents of an individual container does not have to fumble in separating an individual container from the package structure nor disturb its other containers.

When removing an individual container from the package structure, the user does not have to fumble in separating that container from the other containers because each container is joined to the cover structure only by its empty end and may be readily torn therefrom by a simple pull on the elongated container freely hanging along the cutting edge 44 of the integral recess, without affecting the other containers and their sealed contents. The contents of the container unit cannot be spilled because the character of the package structure forces the user to tear off the container with the torn-off end facing upwardly.

Alternatively by arranging two or more rows of containers 45 in the recess 41 of the backing sheet, in the way shown in Figs. 1 to 3, and making the recess strip 42 and binding strips 46, separating the rows of bags, of sufficient stiffness, the edge of each strip overlying each row of bags serves as a cutting edge for the row of bags lying in the recess behind it. By arranging the cutting edges so that the cutting edge overlying each row of bags projects slightly beyond the cutting edge of the next outer row of bags, each cutting edge has equal effectiveness in facilitating the tearing off of the individual containers from the package structure.

The package structure of the invention as illustrated in Figs. 1 to 3 resembles thus in its arrangement the popular matchbook structures, the individual baglike containers being readily torn off across the overlying sheet cover portion without spilling the contents of the container and without impairing or in any way affecting the purity and the quality of the contents of the other containers of the package structure. The package structure of the invention has thus all the advantages inherent in structures of the matchbook type, and at the same time overcomes the difficulties heretofore encountered in dispensing in measured quantities powdered, granular, tablet and like products requiring protection against spilling, contamination, deterioration, or the like.

In Fig. 5, is shown another package structure

of the invention. It comprises a cover structure 48-49-43, similar to that of Figs. 1 to 3. Two rows of previously filled containers 50, of the envelope or flat bag type, as shown in Figs. 18 and 19, respectively, have their upper empty ends clamped within the recess 41 as in the structure of Figs. 1 to 3 so that the cover tongue 53 may be inserted behind the edge of the slit 54 formed in the recess strip 42. The bags 50 are of the envelope type, as shown in Fig. 18, and each row of bags may be formed in a continuous operation by sealing the overlapping edges of the upper open end of each filled bag to an overlying mounting strip 51. The mounting strip 51 may be made of a lamination, the inner layer of which is formed of a stiffer material than cardboard, for instance, thin sheet metal having a slightly projecting edge 52 designed to serve as a cutting edge across which the individual bags may be torn off. The front row of the bag assembly is placed slightly higher than the rear row so that after tearing off the bags of the first row the cutting edge 52 overlying the second row of bags is exposed and acts as an effective cutting edge for those in that recess.

Alternatively, the mounting strip 51 on which the rows of bags 50 are assembled prior to forming the package structure shown in Fig. 5, may be made of a single thin sheet strip of material, such as metal, having sufficient strength to serve as a mounting strip for each row of bags in a continuous process production method, and at the same time sufficient stiffness so that its exposed edge shall serve in the package structure as a cutting edge. Such structures are useful when using containers of sheet material having great tearing strength, such as cellulose, or rubber hydrochloride film.

In the form of the package structure shown in Fig. 5, a disengageable closure junction between the cover sheet 43 and the backing sheet 40 is formed by providing the cover sheet 43 with a flat tongue projection 53 narrower than its width and arranged to fit within a slit 54 provided on the overlying strip 42 of the backing sheet 40 which forms the recess 41 so as to be retained therein in the closed condition of the package structure in a way similar to the package structure of Figs. 6 and 7 described hereinafter.

This arrangement of the detachable closure junction between the cover flap and the backing sheet makes it possible to place the clamping staples 49 near the free edges of the mounting strips 51 and the outer recess strip 42, thereby increasing their stiffness and rendering their free edges more effective as cutting edges for tearing off the individual container bags from the package structure.

In Fig. 6 is shown another package structure exemplifying the invention. It comprises a cover sheet folded into a book-shaped structure, as in Figs. 1 to 3, composed of a backing sheet 40 having on one side a recess 41 formed by doubly folded sheet portions 55, 56 arranged so that the edge 57 joining the overlying retaining sheet strip 55 and the additional sheet strip 56 forms a reinforced stiff cutting edge. The empty ends of the individual bags 50 may be fastened either within the integral recess formed by the doubly folded edge portion 56 and the backing sheet 40, as in Figs. 1 to 3, or as shown in Fig. 6, the empty ends of the bags may be fastened in the recess between the two folded-over sheet portions 55, 56 forming the cutting edge portion 57. The several layers of the supporting sheet forming

the folded structure in which the empty ends of the bags are clamped may be joined to each other either by cementitious material or by a crimping operation, or by continuous stitching. Alternatively, they may be clamped by staples 49 as in Figs. 1 to 3.

By placing the clamping staples 49 near the edge of the fold forming the cutting edge 57, its stiffness is increased and it is rendered much more effective as a cutting edge for bag materials having even a relatively large tearing resistance.

The edge of the cover sheet which overlaps the empty ends of the bags 50 may serve as a mounting or binding strip for assembling the individual bags 50 in a continuous production process before the enclosure sheet 40-43-55-56 is folded into its final shape. When the edge of the enclosure sheet is used for mounting the individual bags in their proper grouping, the individual package structures, each enclosing a plurality of dispensing container units 50, may be formed either by cutting the continuous enclosure sheet with the containers fastened thereto into multiple container sections before the folding operation or after the completion of the folding operation.

As shown in Figs. 7 and 8 the individual bags of each row of bags may be assembled in overlapped relation.

As in the package structure of Fig. 5, the cover flap 43 is shown provided with a flat tongue 53 for insertion into a slit 54 of the facing folded-over portion of the backing sheet 40 so as to retain the cover 43 in the closed position in which it forms with the backing sheet 40 a protective enclosure for the containers and their contents which are suspended in the interior space of the enclosure.

In the form of the package structure shown in Fig. 5, two rows of envelope-type bags 50 have their empty ends clamped within a recess 41 of an enclosure structure 40-42-43, similar to that of Figs. 1 to 3. In making a package structure of the type shown in Fig. 5, each row of bags may be independently assembled on a mounting strip 46 by a spotting or crimping operation, and two or more superposed rows of bags, each formed of a length of mounting strip 46 and a row of dispensing containers joined thereto, may be then fastened within the integral recess 41 in a continuous process operation.

In order to facilitate the tearing off of the bags, particularly if the bags are of a material having great tear resistance, metallic strips 52 may be placed back of the interior faces of the recess or mounting strips so as to provide sharp cutting edges overlying each row of bags and enable easy tearing off of each individual bag, the cutting edge strip 52 for the back recess row of bags being arranged to project slightly beyond the cutting edge overlying the outer recess row of bags, so as to assure that each container of each row of bags may be easily torn off across its overlying cutting edge.

Such metallic cutting edge strips 52 may be united, as by cementing, to the overlying mounting strips, or the metallic cutting edge strips 52 may be used as the mounting or binding strips for assembling the bags without resort to mounting strips 46 of paper cardboard or the like.

In the form shown in Figs. 9 and 10, two rows of bags 50 have their upper empty end portions fastened, as in Figs. 18 and 19, to the outer edge portion of the relatively stiff binding strip 46, and the so-assembled structure is then formed 75

into multiple container package structures of the type shown in Fig. 9 by folding and clamping the mounting strip 46 with the containers fastened thereon, or, alternatively, an assembly such as shown in Fig. 16 with its folded sheet strip 72, within a cover structure 40-42-43, as in the structure of Figs. 1 to 3. In the form shown in Fig. 9, the bags of the front recess row are staggered relatively to the bags of the rear recess row so as to keep down the overall thickness of the several rows of bags and the thickness of the package structure.

In Fig. 11 is shown a package structure of the invention in which each package is formed of powder-fold containers 65 of the type shown in Fig. 20. As shown in Fig. 20, each such powder-fold type container is formed by first folding a sheet strip along its middle line around the substance and then folding the overlapping edges of the folded sheet into a double fold. Each so-folded formation is then folded at its center as indicated at 66. Either one or the both halves of such fold may be used to seal, without adhesive, the contents which are to be dispensed. In utilizing such fold-type containers for making a package structure of the type shown in Fig. 11, the filled folds seen in Fig. 12 may have their ends joined to the outer edge of a binding strip 67, and the two overlapping ends of each fold are held sealed by the clamping junction between the mounting strip 46 and the underlying portion of the cover sheet 40. Alternatively, the overlapping ends of a row of such folds may be sealed within a folded over mounting strip, in the way indicated at 72 in Fig. 14, before being mounted on the backing sheet.

One or more rows of such powder-fold containers may be clamped to the backing sheet 40 as by cementing or by staples 49. As shown in Fig. 11, the mounting and cover strip 46 forms with the backing sheet 40 the recess within which the empty ends of the folds 65 are fastened. As in the previously described package structures, the backing sheet 40 is provided with a cover flap 43 the free edge of which fits behind the cutting edge of the mounting strip 46 and serves to retain the cover flap 43 in a way similar to the structure of Figs. 1 to 3. The mounting strip 46 for the package structure of Fig. 11 may be made of stiff cardboard or a metal strip backing may be secured to its underside so as to assure that powder-folds having great tear resistance may be readily torn off across the cutting edge.

In Fig. 13 is shown a package structure of the invention formed with two rows of containers mounted on a common mounting strip in the way illustrated in Fig. 16. As shown in Fig. 16, rows of filled containers 45 have their empty ends sealed and fastened, as by spotting, cementing or crimping, to the opposite edge portions of a mounting strip 72 of suitable material, such as strong paper. The mounting strip 72 with the two rows of containers 45 is then folded along its center line 73 and fastened within the integral recess 41 of a cover structure 40-43 of the type shown in Figs. 1 to 3. The free edge of the recess strip 44 serves as a cutting edge for the outer row of containers 45 and a separate cutting edge may be provided for the back row of containers 45 by clamping a binding strip 74 of relatively stiff material, such as cardboard, between the overlapping sides of the mounting strip 72, the strip 74 having an edge projecting slightly beyond the edge of the integral recess strip 44 so as to serve as an effec-

tive cutting edge for the back recess row of container bags.

Alternatively, two rows of containers 45 may be mounted on a common binding strip 12 of strong material, such as cardboard, and the strip 12 may be folded along a bend line 13, in the way shown in Fig. 14 so that the facing sides of the mounting strip 12 then overlap the empty ends of the bags to form a recess in which the empty ends of the two rows of containers are fastened. The mounting strip 12 so bent to form a recess is secured as by staples 49, to the backing sheet 40 of a folded book-like protective sheet structure, having on its opposite sides a cover 43 and an overlapping strip 42 completing an enclosure around the rows of containers 45 suspended on the backing sheet. A tongue 53 extending from the cover sheet 43 shaped to fit and be retained within a slot 54 of the overlapping strip 42 of the backing sheet forms a disengageable junction for holding the cover 43 in the closed position in a way analogous to the package structures of Figs. 5 and 6.

As in the package structure of Fig. 13, a strip 14 of stiff material may be interposed between the two rows of bags of Fig. 14 so as to provide a recess for each row of bags, the edge of the strip 14 bounding the inner recess serving as a cutting edge for the rear row of bags, and the portion of the mounting strip 12 overlying the outer recess in which the outer row of bags is held, serving as a cutting edge therefor.

In Fig. 15 is shown another form of package structure of the invention in which an enclosure sheet is folded along a center line 11 to form two backing sheets 18 which when folded form two facing leaves of a book-like cover structure. The opposite edges of the two facing leaves 18 have extensions 19 overlapping the adjacent faces of the two leaves 18 to form therewith two recesses 41 in which are fastened the empty ends of rows of freely suspended containers 45, each container being clamped within its recess in a manner similar to those described in connection with any one of the Figs. 1 to 13.

In Fig. 17 is shown another way of forming a row of containers for a package structure of the invention. A sheet 80, out of which the containers are to be made, is folded along its center line, in a way similar to the fold formed by the facing pages 40 and 43 of the enclosure structure of Fig. 11. The overlapping facing portions of the so-folded sheet formation are severed along the lines 81 so as to provide two facing rows of tongue-like freely suspended sheet sections. By making the sheet 80 of a material that fuses under pressure and heat, such as wax paper, fusible cellulosic sheet material, or rubber hydrochloride, the individual sheet sections 82 which are suspended from the common junction strip 83 may be united at the side edges 84 and bottom edges 85 so as to form a row of containers suspended on the common junction strip 83 which may be utilized as a mounting strip in making of such container assembly package structures of the invention.

When a package structure of the invention is made from rows of containers formed in the way shown in Fig. 17, the individual containers 82 may be filled, after their side edges 84 are sealed, through their open bottom ends 85. Then the open ends of the containers 82 are sealed and bound in the cover structure. Alternatively, the folded edge of the sheet which

forms the junction strip 83 may be cut open to permit filling the individual containers through their open top ends before the junction portion 83 is sealed and mounted within the folded book-like enclosure structure.

A plurality of individual bags or containers can be assembled on a common binding strip and mounted within a common holder, and each bag or container can be detached from the holder as the need arises simply by tearing it in proximity of the retaining lip 122. Spilling of the contents of the bag detached can be easily prevented by holding the package so that the torn-off end of the bag faces upwardly.

In Figs. 22 to 25 I illustrate a method of producing from a single blank a row of individual containers integrally extending from a common binding strip for mounting in a folder, such as shown in Fig. 2. As shown in Fig. 22, a paper blank in the form of an elongated strip 138 is slit at equal longitudinal intervals along lines 139, 140, 141, 142, extending from the bottom edge 143 of the strip up to a point, such as 144, at a certain distance from the top edge 145. Said slits 139 to 142 separate the strip into five individual package blanks 146, 147, 148, 149, 150, which are joined by a top binding strip 151.

The folding flaps of each individual package or container are obtained by severing said flaps from the top strip 151 by means of longitudinal slits 152, reaching inwardly from each lateral edge of each individual blank to a point defining the lateral edge of the package or container in its completed form, the lateral edges of each container being defined by folding dotted lines 153, 154, as shown.

The construction illustrated is intended for the production of individual package units of the expandable type formed with lateral gussets and, therefore, dotted folding lines 153, 154 are supplemented by parallel dotted folding lines 155, 156, corresponding to the bottom of each gusset and by dotted folding lines 157, 158, corresponding to the other fold of each gusset.

As shown in Fig. 23, the individual blank 146 at the right is shown after its side flaps have been folded inwardly along folding lines 153, 154, and outwardly along folding lines 155, 156. At a subsequent stage shown in connection with the blank immediately at the left, the flaps 159, 160 of the individual package have been folded inwardly along the folding lines 157, 158, one of the flaps overlapping the other and being secured thereto by means of an adhesive or in any other convenient manner.

In Fig. 25 are shown the folding lines designated by the same reference characters, the front flap 160 overlapping the front fold 159, and the resulting structure being in the form of a relatively flat expandible tube downwardly extending from the strip 151.

The tip end of each tubular structure thus obtained in its flat or collapsed condition is then turned inwardly and pasted or otherwise secured onto the body of the structure, as shown at 161, forming a closed end of the container. The strip portion 151 is then bent downwardly against the body of the containers extending therefrom, forming a closure for the upper-open end of said containers, the folding of said strip portion being, of course, effected after the filling of the individual containers.

The strip portion 151 of the resulting assembly may then be folded lengthwise upon itself along the dotted line 151', shown in Fig. 23, in a

manner causing the two packages at the right of Fig. 23 to occupy the spaces between the other packages as shown in Fig. 24, said packages 162 being designated in Fig. 23 by reference characters 146', 147', 148', 149' and 150', thus completing a multi-container unit ready for mounting within the recess of a folded enclosure sheet.

In Figs. 26 to 29 I illustrate another method of producing a package unit from a single blank. The height from top to bottom of the blank used is equivalent to twice the height of the package unit to be obtained therefrom. The blank is slit along spaced parallel vertical lines 167 and along the aligned horizontal lines 168, 169 to provide a series of sheet sections 170 provided with lateral flaps 171 extending between two border strips 172. Alternatively, the portion 169 may be left uncut, to provide integral gussets, shown in Fig. 28.

The flaps 171 of the individual sheet sections 170 are then folded, as shown in the right part of Fig. 26, and the blank with the folded flaps is then folded along the center line 174 into the shape shown in Fig. 27. The flaps 171 of each sheet section 170 are then joined, as by an adhesive substance, either in the way shown in Fig. 28 or Fig. 29, so as to form a row of bags 170 suspended on a common binding or mounting strip formed of the two facing end strips 172.

After the containers 170 have been filled the two strip portions 172 can be joined to each other, or else, if preferred, the sealing of the containers can take place when the rows of containers 170 assembled on the strip 172 are fastened in position within the holder, in the manner indicated in Fig. 30.

In Fig. 30 is shown a package structure of the invention in which two rows of containers 189 and 191, such as described in connection with Figs. 26 to 29, are secured to the opposite edges of a cover sheet 188, so that the resulting structure will include two sets of containers.

The rows of containers 191 are held between the backing sheet 188 and the turned-in edge portions 192 thereof, forming the retaining lip and extending to form the closing flap 193, foldable over the rows of containers 191.

This arrangement makes it possible to supply in the same holder two different products which might be identified by making the package units of different colors. This is an advantage especially in such cases where two different substances should be mixed together at the moment of use.

Many other modifications of the invention will suggest themselves to those skilled in the art. It is accordingly desired that the appended claims be given a broad construction commensurate with the scope of the invention as explained and disclosed in the specification.

I claim:

1. In a multiple-container dispensing package, a protective sheet enclosure having a backing sheet and a cover sheet folded thereover to protect the interior space between said sheets, a relatively narrow overlying retaining sheet strip extending over a portion of said backing sheet to form along the interior surface of said backing sheet an elongated recess bounded by an edge of said strip, at least one additional sheet strip and at least one row of a plurality of tearable baglike containers extending from said additional strip and holding sealed in expanded portions of their interior fractional amounts of a dispensable substance, said additional strip and the empty

end portions of said containers being fastened behind the edge of said overlying retaining strip within the recess formed on said backing sheet, the fastened end portions of each container constituting the sole junction of the container to the backing sheet and to the other containers fastened to said backing sheet so that substantially the entire filled length of each container is freely suspended in front of said backing sheet and that each of said containers may be removed individually from said protective enclosure by merely tearing it off across the edge of one of said sheet strips without requiring disjoining from the suspended portions of the other containers fastened to said backing sheet.

2. In a multiple-container dispensing package, a protective sheet enclosure having a backing sheet and a cover sheet folded thereover to protect the interior space between said sheets, a relatively narrow overlying retaining sheet strip extending over a portion of said backing sheet to form along the interior surface of said backing sheet an elongated recess bounded by an edge of said strip, at least one additional sheet strip and at least one row of a plurality of tearable baglike containers attached to and extending from said additional strip and holding sealed in expanded portions of their interior fractional amounts of a dispensable substance, said additional strip and the empty end portions of said containers being fastened behind the edge of said overlying retaining strip within the recess formed on said backing sheet, the fastened end portions of each container constituting the sole junction of the container to the backing sheet and to the other containers fastened to said backing sheet so that substantially the entire filled length of each container is freely suspended in front of said backing sheet and that each of said containers may be removed individually from said protective enclosure by merely tearing it off across the edge of one of said sheet strips without requiring disjoining from the suspended portions of the other containers fastened to said backing sheet.

3. In a multiple-container dispensing package, a protective sheet enclosure having a backing sheet and a cover sheet folded thereover to protect the interior space between said sheets, a relatively narrow overlying retaining sheet strip extending over a portion of said backing sheet to form along the interior surface of said backing sheet an elongated recess bounded by an edge of said strip, at least one additional sheet strip and at least one row of a plurality of tearable baglike containers integrally extending from said additional strip and holding sealed in expanded portions of their interior fractional amounts of a dispensable substance, said additional strip and the empty end portions of said containers being fastened behind the edge of said overlying retaining strip within the recess formed on said backing sheet, the fastened end portions of each container constituting the sole junction of the container to the backing sheet and to the other containers fastened to said backing sheet so that substantially the entire filled length of each container is freely suspended in front of said backing sheet and that each of said containers may be removed individually from said protective enclosure by merely tearing it off across the edge of one of said sheet strips without requiring disjoining from the suspended portions of the other containers fastened to said backing sheet.

4. In a multiple-container dispensing package, a protective sheet enclosure having a backing

sheet and a cover sheet folded thereover to protect the interior space between said sheets, a relatively narrow overlying retaining sheet strip extending over a portion of said backing sheet to form along the interior surface of said backing sheet an elongated recess bounded by an edge of said strip, one additional sheet strip and at least one row of a plurality of tearable baglike containers extending from said additional strip and holding sealed in expanded portions of their interior fractional amounts of a dispensable substance, said additional strip and the empty end portions of said containers being fastened behind the edge of said overlying retaining strip within the recess formed on said backing sheet, said retaining strip being formed by a sheet portion extending integrally from said backing sheet, the fastened end portions of each container constituting the sole junction of the container to the backing sheet and to the other containers fastened to said backing sheet so that substantially the entire filled length of each container is freely suspended in front of said backing sheet and that each of said containers may be removed individually from said protective enclosure by merely tearing it off across the edge of one of said sheet strips without requiring disjoining from the suspended portions of the other containers fastened to said backing sheet.

5. In a multiple-container dispensing package, a protective sheet enclosure having a backing sheet and a cover sheet folded thereover to protect the interior space between said sheets, a relatively narrow overlying retaining sheet strip extending over a portion of said backing sheet to form along the interior surface of said backing sheet an elongated recess bounded by an edge of said strip, one additional sheet strip and at least one row of a plurality of tearable baglike containers extending from said additional strip and holding sealed in expanded portions of their interior fractional amounts of a dispensable substance, said additional strip and the empty end portions of said containers being fastened behind the edge of said overlying retaining strip within the recess formed on said backing sheet, said additional sheet strip being formed by a sheet portion extending integrally from said retaining strip, the fastened end portions of each container constituting the sole junction of the container to the backing sheet and to the other containers fastened to said backing sheet so that substantially the entire filled length of each container is freely suspended in front of said backing sheet and that each of said containers may be removed individually from said protective enclosure by merely tearing it off across the edge of one of said sheet strips without requiring disjoining from the suspended portions of the other containers fastened to said backing sheet.

6. In a multiple-container dispensing package, a protective sheet enclosure having a backing sheet and a cover sheet folded thereover to protect the interior space between said sheets, a relatively narrow overlying retaining sheet strip extending over a portion of said backing sheet to form along the interior surface of said backing sheet an elongated recess bounded by an edge of said strip, one additional sheet strip and at least one row of a plurality of tearable baglike containers extending from said additional strip and holding sealed in expanded portions of their interior fractional amounts of a dispensable substance, said additional strip and the empty end portions of said containers being fastened be-

hind the edge of said overlying retaining strip within the recess formed on said backing sheet, said additional sheet strip being formed by a sheet portion extending integrally from said retaining strip, said retaining strip being formed by a sheet portion extending integrally from said backing sheet, the fastened end portions of each container constituting the sole junction of the container to the backing sheet and to the other containers fastened to said backing sheet so that substantially the entire filled length of each container is freely suspended in front of said backing sheet and that each of said containers may be removed individually from said protective enclosure by merely tearing it off across the edge of one of said sheet strips without requiring disjoining from the suspended portions of the other containers fastened to said backing sheet.

7. In a multiple-container dispensing package, a protective sheet enclosure having a backing sheet and a cover sheet folded thereover to protect the interior space between said sheets, at least two superposed relatively narrow sheet strips overlying a portion of said backing sheet to form along the interior surface of said backing sheet a plurality of superposed elongated recesses, each strip having an edge constituting the outer boundary for the recess formed by the strip, each of said recesses having fastened therein behind the edge of the overlying strip the empty ends of at least one row of a plurality of laterally spaced tearable baglike containers holding sealed in expanded portions of their interior fractional amounts of a dispensable substance, the fastened end portions of each container constituting the only junction of the container to the backing sheet and to the other containers fastened to said backing sheet so that substantially the entire filled length of each container is freely suspended in front of said backing sheet and that each of said containers may be removed individually from said protective sheet enclosure by merely tearing it off across the free edge portion of one of said sheet strips without requiring disjoining from the suspended portions of the other containers fastened to said backing sheet.

8. In a multiple-container dispensing package, a protective sheet enclosure having a backing sheet and a cover sheet folded thereover to protect the interior space between said sheets, at least two superposed relatively narrow sheet strips overlying a portion of said backing sheet to form along the interior surface of said backing sheet a plurality of superposed elongated recesses each strip having an edge constituting the outer boundary for the recess formed by the strip, each of said recesses having fastened therein behind the edge of the overlying strip the empty ends of at least one row of a plurality of laterally spaced tearable baglike containers holding sealed in expanded portions of their interior fractional amounts of a dispensable substance, the fastened end portions of each container constituting the only junction of the container to the backing sheet and to the other containers fastened to said backing sheet so that substantially the entire filled length of each container is freely suspended in front of said backing sheet and that each of said containers may be removed individually from said protective sheet enclosure by merely tearing it off across the free edge portion of the next adjacent sheet strip without requiring disjoining from the suspended portions of the other containers fastened to said backing sheet, said cover sheet having a disengageable junction portion for

holding it in closed position in front of said backing sheet.

9. In a multiple-container dispensing package, a protective sheet enclosure having a backing sheet and a cover sheet folded thereover to protect the interior space between said sheets, at least two superposed relatively narrow sheet strips overlying a portion of said backing sheet to form along the interior surface of said backing sheet a plurality of superposed elongated recesses, each strip having an edge constituting the outer boundary for the recess formed by the strip, each of said recesses having fastened therein behind the edge of the overlying strip the empty ends of at least one row of a plurality of laterally spaced tearable baglike containers holding sealed in expanded portions of their interior fractional amounts of a dispensable substance, the fastened end portions of each container constituting the only junction of the container to the backing sheet and to the other containers fastened to said backing sheet so that substantially the entire filled length of each container is freely suspended in front of said backing sheet and that each of said containers may be removed individually from said protective sheet enclosure by merely tearing it off across the free edge portion of the next adjacent overlying sheet strip without requiring disjoining from the suspended portions of the other containers fastened to said backing sheet, said strips having sufficient stiffness for carrying said containers prior to fastening on said backing sheet and their edges having sufficient stiffness to serve as an effective cutting edge for enabling the tearing off of the individual containers across said edge.

10. In a multiple-container dispensing pack-

age, a protective sheet enclosure having a backing sheet and a cover sheet folded thereover to protect the interior space between said sheets, at least two superposed relatively narrow sheet strips overlying a portion of said backing sheet to form along the interior surface of said backing sheet a plurality of superposed elongated recesses, each strip having an edge constituting the outer boundary for the recess formed by the strip, each of said recesses having fastened therein behind the edge of the overlying strip the empty ends of at least one row of a plurality of laterally spaced tearable baglike containers holding sealed in expanded portions of their interior fractional amounts of a dispensable substance, the fastened end portions of each container constituting the only junction of the container to the backing sheet and to the other containers fastened to said backing sheet so that substantially the entire filled length of each container is freely suspended in front of said backing sheet and that each of said containers may be removed individually from said protective sheet enclosure by merely tearing it off across the free edge portion of the next adjacent overlying sheet strip without requiring disjoining from the suspended portions of the other containers fastened to said backing sheet, said strips having sufficient stiffness for carrying said containers prior to fastening on said backing sheet and their edges having sufficient stiffness to serve as an effective cutting edge for enabling the tearing off of the individual containers across said edge, said cover sheet having a disengageable junction portion for holding it in closed position in front of said backing sheet.

ALFRED B. DRULLARD.
